Patented June 7, 1921.

FIG. 2.

FIG. 1.

INVENTOR.

Lionel Moses,
by Joseph A. Miller

ATTORNEY.

UNITED STATES PATENT OFFICE.

LIONEL MOSES, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE FOR SPOONS, FORKS, OR SIMILAR ARTICLES.

58,099.

Specification for Design.

Patented June 7, 1921.

Application filed February 10, 1920. Serial No. 357,685. Term of patent 14 years.

To all whom it may concern:

Be it known that I, LIONEL MOSES, a citizen of the United States, and a resident of Providence, in the county of Providence and State of Rhode Island, have invented a new, original, and ornamental Design for a Handle for Spoons, Forks, or Similar Articles, of which the following is a specification, reference being had to the accompanying drawing, forming part thereof.

Figure 1 is a view of the obverse side of the handle, showing my design.

Fig. 2 is a view of the reverse side of the handle, showing my design.

I claim—

The ornamental design for a handle for spoons, forks, or similar articles, as shown.

LIONEL MOSES.
